Pierre Barnes

ATTORNEY.

UNITED STATES PATENT OFFICE.

FRED A. COOKE, OF SEATTLE, WASHINGTON.

LIFE-PRESERVER.

No. 906,109.

Specification of Letters Patent.

Patented Dec. 8, 1908.

Application filed December 12, 1907. Serial No. 406,123.

To all whom it may concern:

Be it known that I, FRED A. COOKE, a citizen of the United States, residing at Seattle, in the county of King and State of Washington, have invented certain new and useful Improvements in Life-Preservers, of which the following is a specification, reference being had therein to the accompanying drawings.

10 This invention relates to life preservers; and its object is the provision of an appliance of this character of relatively large buoyancy capable of sustaining a swimmer in the water; which will adapt itself to his movements, and not encumber his efforts in reaching safety.

15 A further object of the invention is to provide a life preserver which can be constructed of materials which are not subject to the effects of deterioration, and which can be stored for an unlimited period of time without detracting from its floatative efficiency, or serviceable condition.

20 The invention consists in the novel construction, adaptation and combination of parts, as will be hereinafter described and claimed.

25 In the drawings, Figure 1 is a perspective view of a life preserver embodying my invention and with a portion of the covering fabric broken away to disclose the manner of assembling the buoyant elements. Fig. 2 is a vertical cross sectional view of the same. Fig. 3 is a detail longitudinal section of a 30 floatative element shown detached and in its preferred form; and Fig. 4 is a similar view of a modified form of constructing such elements.

35 According to this invention I employ a plurality of cellular members A which are formed with cylindrical central portions and with closed ends which are desirably formed semi-globular, as indicated by a and a' in Figs. 2 and 3. These members may be 40 constructed of paper composition, or an equivalent metallic material, such as aluminum, which is capable of being drawn or otherwise formed into a thin shell. In the preferred form said members are severally 45 constructed with one of the respective ends, a, removable, to serve as a cap, see Fig. 3, and which are connected with the main portions by interfitting sleeve joints a'', and 50 may be secured thereto as by soldering.

55 Instead of the aforescribed construction, tubular sections A', see Fig. 4, may be

utilized and their ends closed by insertible plug stoppers, such as B, which after being introduced may be reliably held against displacement through pressing ridges a''' into 60 the peripheries of the stoppers.

65 The aforescribed members are made impervious to air and while they are very efficient when filled with air, their buoyant properties are enhanced by exhausting the air therefrom prior to their being sealed. Protection against the corrosive effects of sea-water and deterioration in general of the said members may be afforded by a coating of insoluble varnish. These members are 70 disposed in a life preserver in vertically aligned rows, preferably of two or more in each row, and a sufficient number of such rows are used to furnish a girdle to almost 75 encompass the trunk of a human body.

More particularly, and with reference to Fig. 1, at the back C and at the ends C' which are to be worn at the front are shown with three members in each vertical row while the intermediate portions C'' are comprised of but two members so as to afford arm-holes D thereabove. The various members thus assembled are retained in place and protected by a covering E of a flexible material, such as light canvas, which is securely sewed about the edges by stitches F and by various lines of stitches F' passing from the inner and outer folds of the covering to prevent the dislocation of the members.

80 G represents looped supporting straps which extend upwardly from the preserver for use over a wearer's shoulders, and are provided with adjustment buckles G'.

85 H and H' are strap ends, or cords, extending outwardly from the lateral edges of the preserver and adapted to be respectively tied for securing the device in place.

90 The invention is capable of being made of less bulk than other devices of this character which have come to my notice and that, too, with a greater degree of buoyancy. The buoyant elements, owing to their 100 number and their self-sufficiency, safeguard the effectiveness of the device even should one or more of them become inoperative by being punctured.

105 The mode of assemblage, or articulation of the component receptacles allows considerable flexibility and accommodation to the 110 wearer's movements. And the cells being made impervious to air and of a non-ab-

sorbent character with respect to water, insures the efficiency of the apparatus as a means of saving life, and its durability in withstanding the effects of time.

5 Having described my invention, what I claim, is:

In a life preserver, a series of tubular receptacles having closed ends and arranged in rows, the receptacles of each row being disposed in spaced side by side relation and being disposed so that the individual receptacles of each row are in alinement with those of the adjacent rows, and a covering composed of two sections on opposite sides

of the rows, said sections having marginal 15 extensions which project beyond the rows and are stitched to one another, and lines of stitching connecting said sections and arranged in said spaces between the receptacles, whereby long pockets are provided 20 to receive a plurality of receptacles.

In testimony whereof I affix my signature in presence of two witnesses.

FRED A. COOKE.
